UNITED STATES PATENT OFFICE.

JACOB A. HYLE AND WALTER R. CARMODY, OF CHICAGO, ILLINOIS.

RAILWAY-TIE AND RAIL-FASTENING.

1,039,748.

Specification of Letters Patent.

Patented Oct. 1, 1912.

Application filed June 23, 1912. Serial No. 705,287.

To all whom it may concern:

Be it known that we, JACOB A. HYLE and WALTER R. CARMODY, citizens of the United States, residing at Chicago, in the county of Cook and State of Illinois, have invented certain new and useful Improvements in Railway-Ties and Rail-Fastenings, of which the following is a specification.

Our invention relates to a metallic railway tie and means for securely fastening the tie to the track rails of a steam or electric railway.

The prime object of our invention is to provide an improved metallic railway tie in connection with simple, strong, economical, durable and efficient means for firmly securing the track rails to the said improved metallic tie.

A further object of this invention is to provide novel fastening means for securing the track rails to a metallic railway tie, and means for the insulation of the track rails from the said metallic tie.

Another object is to so secure the track rails to the tie as to prevent the track from getting out of its proper gage or alignment, and act as anti-creeping means to prevent the track rails from creeping, thereby constituting improved means for insuring a maximum degree of safety for the road-beds of railways.

Another object of the invention is to provide means secured between the base of the track rails and the upper surface of the tie which serves as a waterproof insulating and resilient cushion, and to deaden the rumbling and rattling noise common on all railways.

The foregoing and such other objects as may occur from the ensuing description, are attained by the means hereinafter more fully described, and by the combination, arrangement and location of the parts illustrated in the accompanying drawings and particularly set forth in the claims appended hereto.

Reference now being had to the accompanying drawings which form a part of this specification and in which similar numerals of reference indicate like parts, it will be seen that: Figure 1, is a cross-sectional view of the improved railway tie, showing in side elevation a portion of a track rail, and the means for securing said tie to the track rails embodying our invention. Fig. 2, is a side elevation of a portion of our im-

proved railway tie, showing in cross section one of the track rails and the plate and clip for securing the track rail to the tie. Fig. 3, is a perspective view of our improved metallic railway tie. Fig. 4, is a plan view of a portion of a railway road-bed showing a portion of a track rail secured to a plurality of railway ties. Fig. 5 is a perspective view of the insulating cushion plate removed from the tie. Fig. 6, is a plan view of the rail securing plate showing a portion bent upward and forward, and the rail securing clip bolted and riveted to the said plate. Fig. 7, is an inverted plan view of the rail securing plate shown in Fig. 6, showing the flat plate before a portion is bent or curved upward and forward. Fig. 8, is a side view of the insulating cushion plate and the rail securing plate, showing the fastening clip removed therefrom. Fig. 9, is in detail, a perspective view of the securing clip and alignment plate bolted and riveted together, and Fig. 10, is a perspective view of the insulating fiber washer which surrounds the headed portion of the securing bolt.

In carrying out our invention, we provide an improved railway tie 1, which may be made from any suitable metal capable of attaining the objects sought to be obtained, hence it may be rolled, pressed, stamped up or formed by suitable dies. The metal shell constituting the railway tie proper is filled in any suitable or desirable manner with concrete material 2, thereby adding weight and strength as well as preventing corrosion on the interior of the tie and forming a solid and rigid interior for the said tie. The tie such as shown in Fig. 3, is made of the same shape and contour throughout its length, and is provided with a plurality of transversely arranged securing bolts or rivets 3, which are passed through the tie from one side to the other, one of which bolts is preferably located at a point beneath the base of each track rail, and serves to prevent the tie from breaking or springing away from the filling material, and thus insuring greater strength to the tie. The upper surface of the tie near each end thereof is provided with openings or perforations 4, to receive the main fastening bolts. Each side of the tie is depressed at 5 in a vertical plane with the openings 4, said depressions forming a pocket portion, the upper portion of the pocket forming

a flattened extension or shoulder 6, which serves as a seat for the headed portion of the securing bolt, and in vertical alinement with said depression 5, the tie at each side thereof extending from the base upward is depressed at 7, to form a vertical recess or groove therein so that a straight securing bolt can be inserted by entering it at the side of the tie at the pocket portion 5, as clearly shown in Figs. 1 and 2.

10 The track rails 7^x may be formed in any suitable shape or contour that will render them applicable or serviceable in connection with our improved rail securing means.

15 A cushion plate 8, formed as shown in Fig. 5, is placed on top of the tie, this plate being made from a number of thicknesses of waterproof paper to the desired degree of thickness constitutes an insulating and 20 resilient cushion between the rail and tie thus serving to prevent the breaking of rails which is now common in the use of wooden ties, and said cushion plate also serves to deaden the rumbling and rattling noise 25 which is common on all railways, and since it is firmly secured between the tie and the securing means hereinafter more fully described, it will not wear out by frictional contact, for the reason that the track rail 30 securing means and tie are so rigidly secured together as to render them immovable.

A metallic securing plate 9, formed as shown in Fig. 6, is placed on top of the cushion plate 8, said plate 9 being provided 35 on opposite sides and near each end thereof with openings or perforations 10 and 11. To the upper surface of the plate 9 is rigidly secured near each end thereof a securing clip 12, and an alinement or gage 40 plate 13, said clip and plate having perforations adapted to register with those in plate 9, and each plate 13 is rigidly riveted to the clip 12, the inner edge of each plate 13 resting against the side of the base portion of the rail 7^x to insure its proper 45 alinement and gage, and the inner end 14 of each clip plate 12 extending over and adapted to rest upon the upper surface of the base of the rail. One end of the metallic plate 9 is slit or cut a portion of its 50 length at 15, and the cut portion 16 is then bent upward and over and adapted to rest in contact with the upper surface of the base of the rail. The securing plates 9 are 55 arranged on the ties so that the upturned portion 16 on each tie alternately rests on the upper surface of the base of the rail on the outside and inside of the rail, as clearly shown in Fig. 4 of the drawings, hence the 60 upturned portion 16, being arranged on either side of the rail on every other tie, serves as an additional reserve fastener and in the event of derailment will prevent the rail from turning over or spreading.

65 An opening is formed in the tie near

either side and end thereof and in a vertical line with the opening 4, through which is inserted upwardly at the side of the tie, the main fastening bolt 17, screw-threaded at its upper end and provided with a securing nut 18, the latter resting in contact with the upper surface of the securing clip plate 12. Surrounding the fastening bolt 17 is an insulating fibrous sleeve 18^x, the upper portion of said sleeve terminating in contact with the insulating cushion plate and the lower end of said sleeve resting in contact with an insulating fibrous washer 19 the latter surrounding the head portion of the said fastening bolt to prevent contact 70 by the head of the bolt with the metal portion of the tie, thus securely insulating the bolt from the tie. The fastening bolt is passed upward through the hole in the tie, the cushion plate, the metallic securing 75 plate, the plate 13 and clip securing plate 12, and its screw-threaded end is secured by a fastening nut whereby the securing means is rigidly and firmly secured to the tie and track rails. It will be observed that 80 the clip plate 12 is firmly riveted to plate 13, thus rigidly securing the two pieces together, hence the plate 13 resting against the side of the rail base and being rigid with the clip prevents the turning aside or 85 swerving of the clip plate in the event that the latter should become loose. It will 90 be perceived that each metal securing plate is provided with two securing clip plates and an upturned portion, said clip plates and upturned portion adapted to clamp the 95 upper surface of the base of the rail, and all of these members being bolted solid to the rail and tie prevent the rails from creeping, since to permit creeping the ties 100 and ballast must yield as a unit, and this will not occur since the weight of the ties and ballast will successfully resist the strain of the rolling stock.

It will be obvious that the shape of the tie, the material from which it is made and the secure fastening means prevents the upheaval of ties where frost and excessive moisture is located in the road-bed, such as will occur when wooden ties are used, and 115 uneven upheaval is thus rendered impossible.

Having thus described our invention, what we desire to claim and secure by Letters Patent is:—

1. A metallic railway tie, a solid filling therein, said tie having openings in its upper surface, pockets formed in either side thereof in a vertical line with said openings, and a recess or groove formed in either side of the tie at the base portion thereof in vertical alinement with said pockets.

2. A metallic railway tie, a solid filling therein, said tie having openings in its upper surface, pockets formed in either side 130

- thereof in a vertical line with said openings, said pockets terminating at their upper portion with a flattened shouldered portion, and a recess or groove formed in either side of the tie at the base portion thereof in vertical alinement with said pockets.
3. A metallic railway tie, a solid filling therein, transverse securing bolts or rivets passing through the tie, said tie having openings in its upper surface, pockets formed in either side thereof in a vertical line with said openings, and a recess or groove formed in either side of the tie at the base portion thereof in vertical alinement with said pockets.
4. A metallic railway tie, a solid filling therein, said tie having openings in its upper surface, and rail fastening means comprising a metallic plate having a portion of the plate upturned over the base of the rail, a clip fastening plate extending over the base of the rail, a plate riveted to said clip plate beneath the same, and a fastening bolt passing through a portion of the tie and through each of said plates for securing the rail to said tie.
5. A metallic railway tie, a solid filling therein, said tie having openings in its upper surface, and rail fastening means comprising a metallic plate having a portion of the plate upturned over the base of the rail, a clip fastening plate extending over and in contact with the upper surface of the base of the rail, a plate riveted to the underside of said clip plate with its inner edge in contact with the side of the base of the rail, and a fastening bolt passing through a portion of the tie and through each of said plates, and a securing nut on the end of the bolt for rigidly securing the rail to said tie.
6. A metallic railway tie, a solid filling therein; said tie having openings in its upper surface, and rail fastening means comprising a metallic plate having a portion thereof upturned over the upper surface of the base of the rail, a clip fastening plate extending over the base of the rail, a plate riveted to the underside of said clip plate and in contact with the side of the base of the rail, a fastening bolt passing through a portion of the tie and through each of said plates for securing the rail to said tie, an insulating sleeve surrounding the said bolt within the tie, and an insulating washer surrounding the headed portion of the bolt outside of the tie, whereby said fastening bolt is insulated from the tie.
7. A metallic railway tie, a solid filling therein, said tie having openings in its upper surface, a waterproof insulating resilient cushion plate located on top of the tie, and rail fastening means comprising a metallic plate having a portion of one end thereof upturned over the upper surface of the base of the rail, a clip fastening plate extending over the base of the rail, a plate riveted to the underside of said clip plate and in contact with the side of the base of the rail, and a fastening bolt passing through the cushion plate and each of said plates for rigidly securing the rail to the tie.
8. A railway road-bed comprising railway ties provided with a solid filling, each tie having openings in its upper surface, track rails, and rail fastening means comprising a rail securing plate provided with an upturned portion resting in contact with the upper surface of the rail-base, a clip fastening plate supported near each end of the rail securing plate and extending over the upper surface of the rail base at either side of said base, a plate riveted to the underside of each clip plate and in contact with each side of the base of the rail, and a fastening bolt passing through a portion of the tie and through each of said plates for securing the rail to the said tie.
9. A railway road-bed comprising railway ties provided with a solid filling, each tie having openings in its upper surface, track rails, and rail fastening means consisting of a rail securing plate slit at one end thereof and provided with an upturned portion resting in contact with the upper surface of the rail base, a clip fastening plate supported near each end of said rail securing plate and extending over and in contact with the upper surface of the rail base at either side of said base, a plate riveted to the underside of each clip plate and in contact with each side of the base of the rail, a fastening bolt passing through a portion of the tie and through each of said plates, and a nut fitted to the upper end of said bolt whereby the said rail is rigidly secured to the tie.
10. A railway road bed comprising railway ties provided with a solid filling, each tie having openings in its upper surface, track rails, and rail fastening means consisting of a rail securing plate slit at one end thereof and provided with an upturned portion resting in contact with the upper surface of the rail base, said securing plate being so arranged on each alternate tie that the upturned portion will alternately rest on the inside and the outer side of the rail base, a clip fastening plate supported near each end of the rail securing plate and extending over the upper surface of the rail base at either side of said base, a plate riveted to the underside of each clip plate and in contact with each side of the base of the rail, a fastening bolt passing through a portion of the tie and through each of said plates, and a nut fitted to the upper end of said bolt, whereby the said rail is rigidly secured to the tie.
11. A railway road-bed comprising rail-

way ties provided with a solid filling, each tie having openings in its upper surface, and transverse securing bolts or rivets, track rails, and rail fastening means consisting of 5 a rail securing plate provided with an upturned portion resting in contact with the upper surface of the rail base, said securing plate being so arranged on alternate ties that the upturned portion will alternately 10 clamp the base of the rail on its inner and outer side, a clip fastening plate supported near each end of the rail supporting plate on the upper surface thereof and adapted to clamp the upper surface of the rail base

at either side thereof, a plate riveted to the 15 underside of each clip plate adapted to contact with each side of the base of the rail, a fastening bolt passing through a portion of the tie and through each of said plates, and a nut fitted to the upper end of said bolt for 20 securing the track rail to said tie.

In testimony whereof we affix our signatures in presence of two witnesses.

JACOB A. HYLE.

WALTER R. CARMODY.
